UNITED STATES PATENT OFFICE.

GEORGE MULLER, OF RIDGEWOOD, NEW JERSEY.

AMUSEMENT APPARATUS.

1,141,821.

Specification of Letters Patent.

Patented June 1, 1915.

Application filed May 23, 1914. Serial No. 840,478.

To all whom it may concern:

Be it known that I, GEORGE MULLER, a citizen of the United States, and a resident of Ridgewood, in the county of Bergen and 5 State of New Jersey, have invented a new and Improved Amusement Apparatus, of which the following is a full, clear, and exact description.

The object of the invention is to provide a 10 new and improved amusement apparatus more especially designed for use in pleasure resorts, parks, fairs and like places, and arranged to carry passengers through the air in imitation of a trip in an aeroplane.

15 In order to accomplish the desired result, use is made of a revoluble central mast, a superstructure mounted to rotate with and to slide up and down on the said mast, passenger carriers in the form of imitation flying machines, and flexible connections for suspending the said carriers from the superstructure.

20 A practical embodiment of the invention is represented in the accompanying drawings forming a part of this specification, in which similar characters of reference indicate corresponding parts in all the views.

Figure 1 is a plan view of the amusement apparatus, part of the platform being 25 broken out; Fig. 2 is a vertical section of part of the apparatus; Fig. 3 is a cross section of the same on the line 3—3 of Fig. 2; Fig. 4 is an enlarged cross section of the 30 controlling device for the mechanism employed for raising and lowering the superstructure and its carriers; and Fig. 5 is an enlarged sectional plan view of the mast and the hub of the superstructure, the section being on the line 5—5 of Fig. 3.

35 On a suitably constructed platform A is mounted a vertically disposed bearing B in which turns a mast or a central post C extending a suitable distance above the platform A. A superstructure D, such as is 40 generally used in merry-go-rounds, is provided with a hub D' mounted to slide up and down on the mast C, the hub having a key D² engaging a keyway C' formed on the mast C to cause the superstructure D to rotate with the said mast C.

To the superstructure D are secured flexible connections E, such as ropes or cables, supporting passenger carriers F, each preferably in the form of an aeroplane, provided 45 with wheels F' adapted to travel on the platform A at the time the superstructure D is in

lowermost position, as indicated in Figs. 2 and 3.

The lower end of the mast C extends below the platform A and on this lower end is 50 secured a bevel gear wheel G in mesh with a bevel gear wheel G' secured on a transversely extending shaft H journaled in suitable bearings arranged on the under side of the platform A. The shaft H is connected 55 with a suitable motor I, preferably by the use of a pulley H' secured on the shaft H, and over which pulley passes a belt H² also passing around a pulley H³ secured on the shaft I' of the motor I. The motor I is 60 preferably of the electric type controlled by a suitable switch I² mounted on top of the platform A and within convenient reach of the attendant in charge of the amusement apparatus.

75 The lower end of the hub D' of the superstructure D rests on a cross head J secured to the upper ends of vertically disposed rods J' mounted to slide up and down in suitable bearings B' arranged on opposite sides of 80 the bearing B. The lower ends of the rods J' extend below the platform A and to the lower terminals of the said rods are secured ropes J² extending upwardly and passing over pulleys J³ journaled on the under side 85 of the platform A. The free ends of the ropes J² carry counterweights J⁴ for counterbalancing the superstructure D and its load with a view to insure easy running of the 90 apparatus. To the lower terminals of the rods J' are also secured ropes K extending upwardly and passing over guide pulleys K' and K² arranged on the underside of the platform A to direct the ropes K onto a drum L on which wind and unwind the said 95 ropes K. The drum L is mounted to turn 100 loosely on a shaft N journaled in suitable bearings arranged on the under side of the platform A, and on one end of the shaft N is secured a bevel gear wheel N' in mesh with a bevel gear wheel N² secured on the driving shaft H so that when the latter is rotated from the motor I then a rotary motion is given to the shaft N by the gear wheels N² and N'.

105 A clutch mechanism is used to permit of rotating the drum L with the shaft N and for this purpose the drum L is provided with a notch L' adapted to engage a pin N³ on the shaft N (see Fig. 1), so that when the drum L is shifted to the 110 right and the notch L' engages the pin N³ then the rotary motion of the shaft N is

transmitted to the drum L with a view to wind up the cords K. When this takes place the cords K exert an upward pull on the rods J' to move the latter upward in 5 their bearings B' and in doing so the cross head J lifts the superstructure D and with it the passenger carriers F.

The drum L is provided with a flanged 10 brake wheel L² engaged by a brake band O having one end O' pivoted on a pin P' held on a bracket P secured to the under side of the platform A. The other end O² of the brake band O forms a handle and is provided with an aperture O³ through 15 which extends the pin P' to form a fulcrum for the end O² with a view to allow the operator to impart a swinging motion to the brake band O to shift the drum L on the shaft N with a view to move the notch L' 20 into and out of engagement with the pin N³ according to the direction in which the handle O² of the brake band O is moved at a time. Normally the handle end O² of the 25 brake band O rests on the bottom of the bracket P and when the handle end is in this position the brake band O is loose relatively to the brake wheel L². When the operator swings the handle end O² upward then the 30 brake band O is tightened around the brake wheel L² to brake the latter. In practice the handle end O² of the brake band O engages a slot Q' in a hand lever Q fulcrumed on a bracket Q² attached to the under side of the 35 platform A. The hand lever Q extends to the top of the platform adjacent the switch I² so as to be within convenient reach of the attendant in charge of the machine. The under side of the handle end O² of the brake band O is engaged by a button R' of a lever 40 R fulcrumed on a bracket R² attached to the under side of the platform A, and the said lever R is provided with an upwardly extending rod R³ reaching a short distance above the platform A so as to be within convenient reach of the attendant's foot. Thus 45 when the operator presses the rod R³ downward an upward swinging motion is given to the handle end O² to apply the brake band O on the brake wheel L². It is understood 50 that when the operator shifts the lever Q sidewise a sidewise swinging motion is given to the handle end O² of the brake band O to move the drum L on the shaft N with a view 55 to engage the notch L' with the pin L³ or to disengage the notch L' from the said pin, as previously explained.

The upper ends of the bearings B' are 60 provided with springs S through which extend the rods J', and the said springs form a cushion for the cross head J when the latter moves into lowermost position, as shown in Figs. 2 and 3. The top of the mast C is 65 provided with a collar C² to limit the upward sliding movement of the superstructure D on the mast C.

The operation is as follows: When the several parts are in the position shown in Figs. 2 and 3, the wheels F' are on the platform A, and when the motor I is started a rotary motion is transmitted by the shaft H 70 and the gear wheels G', G to the mast C to rotate the latter, and as the superstructure D turns with the mast it is evident that the carriers F are carried around in a circle with the wheels F' traveling on the platform A. 75 After the superstructure D has made a few turns the attendant in charge imparts a swinging motion to the left to the lever Q so as to shift the drum L to the right with a view to engage the notch L' with the pin N³, and when this takes place the drum L is rotated from the shaft N rotating in unison with the shaft H. The rotating drum L now winds up the ropes K so that the rods J' are moved upward and in doing so the 80 cross head J lifts the superstructure D and with it the carriers F so that the latter are raised above the platform A and are themselves freely suspended from the superstructure D. It will be noticed that as the superstructure D is rotated and the carriers F are 85 now freely suspended and travel around in a circle they are caused to fly outward by centrifugal force, the flexible connections E permitting such movement. It will also be 90 noticed that the passengers in the carriers F are not only carried around but also upward and outward, thus practically enjoying the sensation of a trip in an aeroplane. When the superstructure D has reached a 95 desired height the attendant in charge swings the lever Q back to its former position to disengage the notch L' from the pin N³, and at the same time the operator presses the pin R³ to cause the brake band O to 100 brake the wheel L² thus holding the drum L against return movement. By the arrangement described the superstructure D can be held in raised position for any 105 desired length of time without interfering with its rotation, and when it is desired to lower the superstructure D the operator gradually releases the brake band O relatively to the brake wheel L² by correspondingly releasing the pin R³. When this takes place the 110 rods J' gradually slide downward and thus lower the superstructure D and with it the carriers F, and when the wheels F' again reach the platform A the operator stops the motor I thus finally bringing the carriers F gradually to a standstill on the platform A. If desired the support D may be raised and lowered any desired distance and as many times as desired during each trip so 115 as to heighten the flying sensation of the passengers.

The amusement apparatus shown and described is comparatively simple in construction and requires but a single attendant for running it.

Having thus described my invention, I claim as new and desire to secure by Letters Patent:

1. An amusement apparatus, comprising 5 a mast mounted to turn on its axis, a superstructure having a hub mounted to slide up and down on the said mast and turning with the latter, passenger carriers suspended from the said superstructure, means for 10 turning the said mast, and means for raising and lowering the said superstructure.

2. An amusement apparatus, comprising 15 a mast mounted to turn on its axis, a superstructure having a hub mounted to slide up and down on the said mast and turning with the latter, passenger carriers suspended from the said superstructure, a driving gear for the said mast, a vertically sliding support for the hub of the superstructure, and 20 raising and lowering means for the said support.

3. An amusement apparatus, comprising 25 a mast mounted to turn on its axis, a superstructure having a hub mounted to slide up and down on the said mast and turning with the latter, passenger carriers suspended from the said superstructure, a driving gear for the said mast, fixed guides, rods slideable in the said guides and arranged on opposite sides of the said mast, a cross head on the upper ends of the said rods and supporting the said hub, and means for imparting an up and down sliding motion to the said rods.

35 4. An amusement apparatus, comprising a mast mounted to turn on its axis, a superstructure having a hub mounted to slide up and down on the said mast and turning with the latter, passenger carriers suspended 40 from the said superstructure, a driving gear for said mast, fixed guides, rods slideable in the said guides and arranged on opposite sides of the said mast, a cross head on the upper ends of the said rods and supporting 45 the said hub, a drum adapted to be driven from the said driving gear, and ropes winding on the said drum and connected with the said rods.

5. An amusement apparatus, comprising 50 a mast mounted to turn on its axis, a superstructure having a hub mounted to slide up and down on the said mast and turning with the latter, passenger carriers suspended from the said superstructure, a driving gear 55 for the said mast, fixed guides, rods slideable in the said guides and arranged on opposite sides of the said mast, a cross head on the upper ends of the said rods and supporting the said hub, a drum, a flexible connection 60 between the drum and the said rods, a drum shaft driven from the said driving gear and on which the said drum is mounted to turn loosely, a clutch for connecting the said drum and shaft, and a brake for 65 braking the drum.

6. An amusement apparatus, comprising a mast mounted to turn on its axis, a superstructure having a hub mounted to slide up and down on the said mast and turning with the latter, passenger carriers suspended 70 from the said superstructure, a driving gear for the said mast, fixed guides, rods slideable in the said guides and arranged on opposite sides of the said mast, a cross head on the upper ends of the said rods and supporting 75 the said hub, a drum, a flexible connection between the said drum and the said rods, a drum shaft driven from the said driving gear and on which the said drum is mounted to turn loosely and to slide in the 80 direction of its axis, clutch members on the said drum and shaft, a brake wheel on the said drum, and a combination brake band and shifting lever engaging the said brake wheel.

85 7. An amusement apparatus, comprising a mast mounted to turn on its axis, a superstructure having a hub mounted to slide up and down on the said mast and turning with the latter, passenger carriers suspended 90 from the said superstructure, a driving gear for the said mast, fixed guides, rods slideable in the said guides and arranged on opposite sides of the said mast, a cross head on the upper ends of the said rods and supporting 95 the said hub, means for imparting an up and down sliding motion to the said rods, and counterbalancing means for the said rods.

100 8. An amusement apparatus, comprising a mast mounted to turn on its axis, a superstructure having a hub mounted to slide up and down on the said mast and turning with the latter, passenger carriers suspended 105 from the said superstructure, a driving gear for the said mast, fixed guides, rods slideable in the said guides and arranged on opposite sides of the said mast, a cross head on the upper ends of the said rods and supporting 110 the said hub, means for imparting an up and down sliding motion to the said rods, and a cushioning device for the said cross head when the latter moves into lowermost position.

115 9. An amusement apparatus, comprising a vertically arranged support mounted to turn on its axis, a superstructure mounted to rotate with said support and to slide up and down thereon, means for rotating said support, means for raising and lowering the 120 superstructure, passenger carriers in the form of imitation flying machines, and flexible connections for suspending the said carriers from the said superstructure to allow the carriers to swing outward by centrifugal 125 force while rotating the superstructure and carriers and raising or lowering the same.

130 10. An amusement apparatus, comprising a platform, a revoluble central mast, a superstructure mounted to rotate with and

- to slide up and down on the said mast, passenger carriers in the form of imitation flying machines provided with wheels adapted to travel on the said platform, flexible connections for suspending the said carriers from the superstructure, driving means for rotating the mast, and means actuated by said driving means for imparting a sliding movement to the said superstructure.
- 10 11. An amusement apparatus, comprising a superstructure mounted to rotate and to slide up and down, passenger carriers suspended from said superstructure, a vertically movable support on which the said superstructure rests, means for rotating the superstructure, and means for raising and lowering the said vertically movable support for the superstructure.
- 15

12. An amusement apparatus, comprising a platform, a revoluble central mast on said platform, a superstructure mounted to slide on the said mast and to turn with the latter, passenger carriers suspended from the said superstructure, a driving gear for turning the mast, a support having guided vertical movement and on which the said superstructure rests, and means for raising and lowering the said support and controlled by the said driving gear.

In testimony whereof I have signed my name to this specification in the presence of two subscribing witnesses.

GEORGE MULLER.
